UNITED STATES PATENT OFFICE.

GEORGE WILSON, OF ALBERT LEA, MINNESOTA.

CONDENSER FOR MOTOR-DRIVEN RAILWAY SECTION-CARS.

1,306,986.

Specification of Letters Patent. Patented June 17, 1919.

Application filed May 15, 1918. Serial No. 234,759.

To all whom it may concern:

Be it known that I, GEORGE WILSON, citizen of the United States, residing at Albert Lea, in the county of Freeborn and

5 State of Minnesota, have invented certain new and useful Improvements in Condensers for Motor-Driven Railway Section-Cars, of which the following is a specification.

This invention relates to an improved condenser and radiator for motor driven railway section cars and has as its primary object to provide a device of this character for condensing the steam or vapor generated in the cooling hopper for the cylinder or cylinders of the car motor and returning the cooled water of condensation to the said hopper.

The invention has as a further object to provide a condenser embodying a relatively 20 large area of radiating surface which will be exposed to the cooling influences of the air as the section car is propelled, for thus effectually condensing the steam from the cooling hopper of the car motor and cooling the 25 water of condensation to be returned to the said hopper.

A further object of the invention is to provide a condenser which may be embodied in the structure of the section car without the 30 necessity for structural change therein and wherein the cooling pan or chamber of the condenser will be supported beneath the seat of the car to be housed and protected thereby.

35 And the invention has as a still further object to provide a construction wherein the cooling pan or chamber of the condenser will be mounted and connected with the cooling hopper of the car motor so as not to interfere with the usual sliding adjustment of the 40 motor for tightening the motor drive belt.

Other and incidental objects will appear as the description proceeds. In the drawings wherein I have illustrated the preferred 45 embodiment of the invention, and wherein similar reference characters designate corresponding parts throughout the several views:

Figure 1 is a side elevation partly broken away, showing my improved condenser in 50 connection with a conventional type of motor driven railway section car,

Fig. 2 is a fragmentary sectional view taken on the line 2—2 of Fig. 1 and more particularly showing the construction and 55 mounting of the cooling pan or chamber of the condenser,

Fig. 3 is a fragmentary side elevation showing a slightly modified form of connection between the cooling chamber of the condenser and the car motor,

60

Fig. 4 is a fragmentary plan view of the modification shown in Fig. 3,

Fig. 5 is a fragmentary side elevation showing a still further modification wherein a pump is employed for circulating the water 65 of the cooling hopper of the motor through the cooling chamber of the condenser,

Fig. 6 is a fragmentary sectional view taken on the line 6—6 of Fig. 5,

Fig. 7 is a fragmentary plan view showing 70 a further modified connection between the cooling chamber of the condenser and the car motor,

Fig. 8 shows a modified form of cooling 75 pan or chamber employing baffles therein, and

Fig. 9 is a fragmentary side elevation showing a further modification of the cooling chamber wherein the cooling pans are 80 arranged in multiple.

80

In order that the construction mounting and operation of my improved condenser may be accurately understood, I have, in the drawings, shown said condenser in connection with a conventional type of motor 85 driven railway section car. Referring more particularly to Fig. 1, it will be seen that this car includes the usual frame 10 to which are connected the car wheels 11. Rising from the frame are pairs of spaced seat 90 standards or posts 12 which support the forward section 13 of the car seat. The rear section of the seat is indicated at 14. One end of this latter section is hinged to the forward section 13 and at its opposite end is 95 equipped with spaced posts 15 for normally supporting the rear section to aline with the forward section. Slidably supported in the usual manner from the frame 10 is a car motor conventionally indicated at 16 and 100 connected with this motor is a hand lever 17 for slidably adjusting the motor longitudinally with respect to the car frame. The motor 16 shown is of the single cylinder type, being provided with a horizontally arranged cylinder 18. Surrounding this cylinder is a suitable water jacket therefor and upstanding from the said cylinder to communicate with the jacket is a cooling hopper 19 adapted to receive a supply of water for 110 maintaining the cylinder of the engine cool. Section car motors are, as is well known,

105

100

105

110

usually equipped with these cooling hoppers in lieu of a radiator, owing to the consequent reduction in cost as well as the lessening of the tendency of the body of water in the 5 hopper to freeze in cold weather. Connected with the drive shaft of the motor is a drive pulley 20 and trained about this pulley and a suitable pulley indicated in dotted lines at 10 21 upon the front axle of the car, is a drive belt 22 for propelling the car from the motor. As will be seen, this belt may be adjustably tensioned by slidably adjusting the motor with respect to the frame 10 of the car through operation of the hand lever 17. 15 Also, it is to be observed that access to the motor may be easily had by swinging the rear section 14 of the seat forwardly to rest upon the forward section of the said seat.

Coming now more particularly to the 20 subject of the present invention I employ a relatively long and shallow closed cooling pan or chamber 23 which is of a width to be freely received between the pairs of side standards 12 and is of a length to extend 25 throughout the length of the forward section 13 of the car seat therebeneath. Swingingly connected in any approved manner with the pan adjacent its forward end, is a pair of links 24 provided at their lower 30 ends with suitable loops receiving a pivot rod 25 therethrough. This pivot rod is arranged to extend between the foremost pair of uprights 12 to connect and brace the uprights of said pair with respect to each 35 other. Swingingly connected in any approved manner with the pan adjacent its rear extremity, is a similar pair of links 26 provided at their lower ends with suitable loops loosely receiving a pivot rod 27 40 therethrough. This pivot rod is arranged to extend between the rearmost pair of the uprights 12 to connect and brace the uprights of this latter pair with respect to each other. The pan will thus be supported 45 by the pairs of links 24 and 26 to rock upon the said pivot rods beneath the forward section 13 of the seat and in this connection it is to be observed that the pan is mounted in a position out of the way while at the 50 same time, the said pan will be housed and protected beneath the seat. Possibility of accidental injury to the pan will thus be reduced to a minimum. Furthermore, no structural change in the seat is required in 55 order to accommodate the pan.

Upstanding from the pan adjacent its forward end is a vent pipe 28 projecting loosely through a suitable slot in the seat section 13 and extending from the rear end 60 of the pan in a plane therewith is a nipple or short section of pipe 29. Threaded into the forward side of the hopper 19 of the car motor 16 at a point above the normal water level in the said hopper, is a similar short 65 section of pipe 30, and uniting these pipe

sections is a hose connection 31 secured to the ends of the said pipe sections in any approved manner. The condensing chamber or pan 23 is thus operatively connected with the hopper 19. Steam or vapors generated in the said hopper will, as will be clear, be directed into the said cooling chamber to be condensed therein whence the water of condensation will gravitate back into the hopper for cooling the body of 70 water contained therein. In this connection it will be noted, as best shown in Fig. 1, that the pivot rod 27 is located in a plane slightly below the pivot rod 25. The cooling chamber is thus inclined longitudinally 75 from its forward end toward its rear end in the direction of the hopper so that as the steam or vapor is condensed in the cooling chamber, the water of condensation will immediately flow back into the hopper. Furthermore, this construction provides an arrangement whereby the flat side faces of the cooling chamber will be presented at 80 an angle to the plane of movement of the car. Consequently, when the car is in motion, currents of air will be caused to impinge against the side faces of the cooling chamber for effectually carrying off heat from the steam or vapor therein and consequently quickly condensing such steam or 85 vapor to be returned at a comparatively low temperature to the engine hopper. This effect is greatly enhanced by the fact that the cooling chamber is shallow and has wide 90 side walls so that a correspondingly large 95 cooling area is presented to the influence of the currents of air striking against the cooling chamber. I accordingly provide a construction whereby the water in the engine hopper will under ordinary circumstances, be prevented from overheating to 100 maintain the cylinder of the motor properly cooled. In order to guard against any danger which would be incident to banking up 105 of steam in the cooling chamber, the vent 110 28 is provided.

Attention is now directed to the fact that since the cooling chamber or pan 23 is mounted to rock upon the seat standards 12, the motor 16 may, by manipulating the hand lever 17 as previously indicated, be shifted upon the car frame for either tightening or loosening the drive belt 22. Thus the presence of my improved condenser upon the car will not in the least interfere with the 115 usual adjustment of the car motor for regulating the tension of the drive belt and, furthermore, it will be seen that adjustment of the belt may be had without likelihood of impairing the connection between the cooling chamber or pan of the condenser and the cooling hopper of the engine motor. 125

In Figs. 3 and 4 of the drawings I have illustrated a slight modification in the invention which relates more particularly to 130

the mounting of the cooling chamber or pan of the condenser and the connection between the said chamber or pan and the car motor. In these figures the cylinder of the motor is 5 conventionally illustrated at 32 and communicating with the jacket of this cylinder is a hopper 33. A cooling chamber or pan is indicated at 34. This pan is substantially identical with the pan of the preferred construction with the exception that the vent therefor is arranged at the rear of the pan. The pan is, as shown in Fig. 4, mounted in rearwardly tilted position between the pairs of standards of the forward section of the 10 seat of the car, these standards being conventionally indicated at 35. Connected with opposite ends of the pan and extending through these standards are brace rods 36 rigidly securing the pan in position thereon. 15 Leading to the forward end of the pan is an inlet pipe 37 which projects rearwardly from the pan toward the engine hopper and is provided with an elbow 38. A pipe 39 leads from the upper end of the hopper to 20 form an elbow 40 alining with the elbow 38. Uniting these elbows is a hose connection 41. Leading from the rear end of the pan or chamber 34 is a pipe 42 which extends rearwardly toward the engine hopper and is 25 provided with an elbow 43. Communicating with the bottom of the water jacket of the cylinder 32 is a pipe 44 which extends upwardly at the adjacent side of the cylinder and thence forwardly and is provided with 30 an elbow 45 alining with the elbow 43. Uniting these elbows is a hose connection 46. Thus it will be seen that steam from the hopper 33 will be directed into the pipe 37 and carried thereby into the cooling chamber 34 35 at its forward end while the water of condensation will flow back through the cooling chamber to enter the return pipe 42 and be introduced into the water jacket of the motor cylinder at the point where the water in the jacket of the said cylinder will be 40 the hottest. The cooled water of condensation will thus greatly tend to maintain the water in the bottom of the water jacket at a temperature corresponding to the body of 45 water in the hopper. This modified construction, therefore, provides a very effective arrangement and it will be noted that since the hose connections 41 and 46 are arranged in a plane at right angles to the plane 50 of adjustment of the car motor, this hose connection will flex when the motor is adjusted for regulating the tension of the drive belt of the car so that it accordingly becomes unnecessary to swingingly mount the cooling 55 chamber or pan 34.

In Figs. 5 and 6 of the drawings, I have illustrated a still further modification of the invention. In these figures, the car motor is indicated at 47 and the cylinder of the motor 60 at 48. Communicating with the water jacket

of this cylinder is a hopper 49. Mounted to swing between the uprights of the car seat as in the preferred construction, is a cooling chamber or pan 50. This pan is identical with the pan of the preferred embodiment of 70 the invention with the exception that a vent 51 for the pan is arranged at the rear end thereof. Leading to the forward end of the pan is an inlet pipe 52 connected to branch pipes 53 entering the pan adjacent its opposite side edges. Projecting forwardly from the upper extremity of the hopper 49 is a pipe 54 which extends within the hopper and is connected with a pump conventionally illustrated at 55, this pump, being preferably 75 located within the hopper to avoid freezing. Uniting the pipes 52 and 54 is a hose connection 56. Leading from the rear end of the cooling chamber is a return pipe 57. A pipe 58 corresponding to the pipe 44 of the 80 prior modification is connected with the water jacket of the motor cylinder 48 at the bottom side of the said jacket and extends forwardly from the hopper 49 in alinement with the pipe 57. Uniting these pipes is 85 a hose connection 59. As will be seen, the motor may thus be slidably adjusted for tensioning the drive belt thereof as in the preferred construction. Journaled in any approved manner upon the hopper 49 is a suitable drive shaft 60 carrying a drive pulley 61. Connected with the drive shaft of the motor 47 is a pulley 62 and trained over these drive pulleys is a belt 63. It will accordingly be clear that when the motor is in 90 operation, the pump 55 will act to force water from the hopper 49 into the cooling chamber or pan 50 to maintain a constant circulation of water through the said chamber for effectually maintaining the cylinder 95 100 of the motor cooled. Under particular working conditions such, for instance, as when the condenser is to be used in connection with a section car employed in hilly country so that the motor will accordingly 105 be subjected to severe work, this present modification of the invention will be found particularly advantageous.

In Fig. 7 of the drawings I have illustrated a still further modification of the invention. In this figure the cooling chamber or pan of the condenser is indicated at 64. This pan is identical with the pan disclosed in the prior modification and is mounted in a similar manner. The hopper of the car 115 motor is indicated at 65. Extending through the forward end of the pan is a pipe 66 corresponding to the pipe 52 of the prior modification and connected with branch pipes 67 entering the pan adjacent its opposite side 120 edges. Leading from the upper end of the hopper is a pipe 68 alining with the pipe 66 and connecting these pipes is a hose connection 69. Leading from the bottom side of the water jacket of the motor is a pipe 70 125 130

corresponding to the pipe 58 of the prior modification but extending at the opposite side of the motor cylinder. A return pipe 71 extends from the rear end of the cooling pan 5 and is united with the pipe 70 by a hose connection 79. As will be seen, the present modification discloses a simple manner of connecting the cooling pan or chamber with the motor without the use of a circulating pump as in the prior modification.

In Fig. 8 I have shown a slightly modified form of cooling pan or chamber. In this figure the pan is indicated at 80. This pan in its general features is substantially identical with the pan of the preferred construction. However, in the present modification, reversely presented vanes or baffles 81 are arranged within the pan so that the water of condensation in flowing back through the pan will be caused to take a tortuous course and traverse the bottom wall of the chamber from side to side to be consequently more effectually cooled before being returned to the cooling hopper of the motor.

In Fig. 9 I have shown a still further modification which also relates more particularly to the cooling chamber employed. In this figure the cooling chamber is made up of a series of superposed cooling pans 82 successively connected at opposite ends thereof so that the steam entering the uppermost pan will be caused to circulate through all of the pans to be condensed and the water of condensation effectually cooled.

Having thus described the invention, what is claimed as new is:

1. The combination with a motor mounted for bodily adjustment and equipped with

a cooling jacket, of a condenser including a cooling chamber, means for supporting the condenser for bodily movement, and an operative connection between the jacket and chamber whereby the condenser may move with the motor upon the adjustment thereof.

2. The combination with a motor mounted for bodily adjustment and equipped with a cooling jacket, of a condenser including a cooling chamber operatively connected with the jacket, and means supporting said chamber for rocking movement whereby said chamber may shift with the motor upon the adjustment thereof.

3. The combination with a motor mounted for bodily adjustment and equipped with a cooling jacket, of a condenser including a cooling chamber, and means forming an operative connection between said jacket and chamber whereby the motor may be adjusted relatively to the chamber.

4. The combination with a motor driven railway section car having a seat supported by standards and having the motor thereof mounted for bodily adjustment upon the car and equipped with a cooling jacket, of a condenser including a cooling chamber mounted between said standards beneath the seat and operatively connected with the jacket, pivot rods extending between and bracing the said standards with respect to each other, and links supporting the cooling chamber to rock upon the said pivot rods whereby the said chamber may shift with the motor upon the adjustment thereof.

In testimony whereof I affix my signature.

GEORGE WILSON. [L.S.]
